Specification for Design.

Patented June 6, 1916.

Application filed April 27, 1916. Serial No. 94,081. Term of patent 7 years.

To all whom it may concern:

Be it known that I, HERMAN F. VOSHARDT, a citizen of the United States, residing at Chicago, in the county of Cook and State of Illinois, have invented a new, original, and ornamental Design for a Support for Bowls for Indirect Lighting, of which the following is a specification, reference being had to the accompanying drawing, forming part thereof.

Figure 1 is a plan view of a support for bowl for indirect lighting, showing my new design. Fig. 2 is a side elevation of the same.

I claim:

The ornamental design for a support for bowl for indirect lighting, as shown.

HERMAN F. VOSHARDT.
